UNITED STATES PATENT OFFICE.

FRANCIS H. RICHARDS, OF HARTFORD, CONNECTICUT, ASSIGNOR, BY MESNE ASSIGNMENTS,
TO AMERICAN TYPOGRAPHIC CORPORATION, A CORPORATION OF NEW JERSEY.

TYPOGRAPHIC MACHINE.

No. 875,212.

Specification of Letters Patent.

Patented Dec. 31, 1907.

Application filed January 13, 1902. Serial No. 89,419.

To all whom it may concern:

Be it known that I, FRANCIS H. RICHARDS, a citizen of the United States, residing at Hartford, in the county of Hartford and State of Connecticut, have invented certain new and useful Improvements in Typographic Machines, of which the following is a specification.

This invention relates to keyboard typographic machines; more especially to that class in which impressions are made by types or type-punches mounted upon or operated by rotating or oscillating members, and is principally intended to provide an improved synchronizing device by means of which a certain sequential and specific relation of each type, type-punch or other impression device, to the keyboard and trains of selective mechanism, is established, subsequently to each operation of said impression device, in order to effect, with certainty, the operation of any desired one of the latter, by means of its correlative key. The relative position of the impression devices established by the synchronizing device, as aforesaid, will, hereinafter, for convenience, be referred to as "zero," and the impression devices as "types."

Another important feature of my invention consists in the improved form of the selective mechanism shown herein, whereby the operation of any key results, with certainty, in the presentation of its correlative type in the proper position for obtaining an impression thereof.

The mechanism operating the turret has been made, by me, the subject of a separate application for Letters Patent, patented March 29, 1906, No. 815,979.

In the drawings relating hereto, Figure 1 is a longitudinal vertical view, partly in elevation and partly in section, showing all of this invention except a portion of the selective mechanism; the section being taken through the median line $x-x$, Figs. 2, 3, 4, and 5; Fig. 2 is a top plan view of the whole series of trains of selective mechanism; the trackers, latches and springs thereof being shown only in dotted lines; Fig. 3 is a top plan view on a larger scale, of a latch plate, latches, frictional springs, trackers, bell cranks, etc., forming portions of the selective trains of mechanism; Fig. 3^a is a modification of a selective train; Fig. 4 is a top plan view of a complete machine; Fig. 5 is a par-

tial top plan view of the driving and turret-rotating mechanisms, the synchronizer-operating levers and other parts; Fig. 6 is a perspective view, partly in section, of the synchronizing mechanism at the commencement of its functional movement; Fig. 7 is a similar view of the same, with the synchronizing movement completed, and Fig. 8 is a rear elevation of the synchronizer actuator.

The references are relatively alike throughout the drawings.

A, A, is a case inclosing a major portion of the machine and serving as a mount for parts of the mechanism. Keys 1, 1, are suitably mounted in a keyboard B, and severally attached to the key-levers 2, 2, fulcrumed at 2', 2'. Links 4, 4, are severally pivotally attached, at their upper ends, to the ends of the key-levers 2, 2, and, at their lower ends, to bell-crank levers 4, 4, fulcrumed on suitable supports, and having their lower ends severally pivotally connected to trackers 5, 5. Springs 3, 3, severally serve to maintain the keys 1, 1, key-levers 2, 2, bell-cranks 4, 4, and trackers 5, 5, in their zero, or non-operative, positions.

The trackers 5, 5, are forked at their inner ends where they severally loosely embrace the outer ends of latches 6, 6, which are reciprocatably mounted in the latch block C, Figs. 2 and 3, and are severally frictionally engaged by the latch springs 6', 6'. The trackers 5, 5, and latches 6, 6, are curved, in order to enable proper connections to be established between the bell-cranks 4, 4, and the latches 6, 6, while maintaining, in the latter, the form required to insure their proper and uniform operation, as hereinafter set forth. Several of the latches 6, 6, as shown in plan view at a, a, a, Fig. 3, and in elevation in Fig. 3^a, are operated without intervention of trackers, their positions relative to the keyboard B, rendering this plan feasible; the outer ends of the latches 6, 6, being severally loosely engaged by the lower ends of the bell-cranks 4, 4.

Rotatably mounted on a fixed vertical pivot D, Figs. 1, 2 and 5, and further supported by a conical journal e, at its upper end, is a turret E, carrying, as shown, two rotating shafts 8, 8, parallel with said pivot D, and each carrying on its lower portion a sleeve 9, reciprocatably but non-rotatably mounted thereon, the rotation of said sleeves 9, 9, on the shafts 8, 8, being prevented by

the splines 8', 8', respectively. Frictional contact, by means not shown, but regulated by the screws 9', 9', serves to maintain the sleeves 9, 9, in any vertical position in which they may be placed on the shafts 8, 8. Collars 8^a, 8^a, at the lower ends of the shafts 8, 8, serve to retain the sleeves 9, 9, on said shafts. On each sleeve 9, is a radially-projecting tappet 9^b, so disposed that when in its zero, or non-operative position, it may be engaged by the inner end of any one of the latches 6, 6, that may be so operated as to then intercept said tappet 9^b, when the turret E is rotated. At the upper end of each sleeve 9, is a spur gear wheel 9^c, to the underside of which is rigidly attached one end of an elevator 9^d, preferably made in the form of a spring, as shown, the free end of the latter being recurved in the form of a flat-faced bevel. The elevators 9^d, partly encircle the sleeves 9, 9. At the lower end of each sleeve 9, and integral therewith, is a radial flange 9^e. The latch-plate F, Figs. 1, 2, 3 and 5, is secured to the case A. An annulus G, having depending bracket arms G' G'', furnished with lugs, is secured by the latter to the upper surface of the latch-plate F. To the interior surface of the annulus G, is immovably attached the internal gear segment g'', and concentrically therewith and below the annulus G, is suspended a curved angle-plate g¹, Fig. 1, one member of which projects inwardly and is beveled, at the inner part, to a knife edge g², which lies slightly below the plane of rotation of the free ends of the elevators 9^d, 9^d. At the rear inside of the case A, is pivotally bracketed a bell-crank-lever 11, one arm of which is arranged to engage the upper surface of either of the radial flanges 9^e, when the turret E is rotated; the other arm of said lever 11, being pivotally attached to a link 11^a, which is slotted at its opposite end and embraces a drive shaft H, upon which is mounted a cam H², which, by means of a cam-roller h², reciprocates the link 11^a.

The train of selective mechanism, thus described, is operated as follows:—A key 1, being depressed, elevates the inner end of its lever 2, and operates the connected bell-crank 4; the depending arm of the latter forces forward the connected tracker 5, which similarly operates a latch 6, so as to cause its inner end to lie in the path of the tappets 9^b, 9^b, when their respective type-wheel shafts 8, 8, are at zero and the turret E, is rotated; the direction of rotation of the latter being left-handed, or from north to west. The key 1, key-lever 2, bell-crank 3, and tracker 4, are all returned to their zero positions by a spring 3; but the latch 6, remains in position, being frictionally retained there by its spring 6', and engages the nearest approaching tappet 9^b, partially rotates thereby the sleeve 9, and also, by means of a

spline 8', partially rotates a shaft 8, with all the parts mounted thereon. The partial rotation, as stated, of a sleeve 9, causes the beveled end of the elevator 9^d, mounted thereon to become engaged with the beveled edge of the curved angle-plate g¹, and, by the combined rotating and sliding motion of one inclined plane upon another, the sleeve 9, is elevated sufficiently to cause the gear-wheel 9^c to engage and mesh with the internal gear segments g''; continued rotation of the turret E, thereby imparting an orbital rotation to the shaft 8, and all parts mounted thereon, including the impression devices. 70 75

At the upper end of each shaft 8, and rigidly secured thereto, is a type-wheel 10, on the periphery of which is formed a series of types, A, B, C, D, etc.; the term "types", being generically used herein, to include all manner of designs of impression devices. 85 The characters are similar on both type-wheels 10, 10, and similarly disposed thereon, respectively, and are severally represented on the keys 1, 1. The before-described operation of any key 1, and its train 90 of selecting mechanism, results in the presentation of its cognate type at the common impression point. The impression having been made, as hereinafter set forth, the cam H², on the drive shaft H, draws forward the link 11^a, by means of the cam-roller h², and so operates one arm of the bell-crank 11, that the other arm thereof depresses the flange 9^e, and the sleeve 9, moving the gear wheel 9^c out of mesh from the internal gear 100 segments g'', and bringing the tappet 9^b, again into the plane of the latches 6, 6. Each of the latches 6, 6, is returned to its zero point, after use, by means of a final cam action of the end of the tappet 9^b, which had 105 been engaged by it. A spring 11^b, serves, by means of the bell-crank 11 and link 11^a, to hold the cam roller h² against the cam H², and prevent backlash in the connections of the parts. 110

The driving mechanism illustrated in the drawing, embodies a pulley K, a drive shaft H, mounted in the bearings L, L, and an actuator M, mounted on said shaft. The driven member of the mechanism is shown as 115 a roller turret N, mounted on a sleeve O, which, with the fixed vertical pivot D, forms the journal bearing for the turret E. The operation of the actuator M, with the roller-turret N, is fully described in the prior application hereinbefore mentioned, and results in an intermittent rotary motion of the turret E, and all parts mounted thereon; the cycle thereof being divided into four unequal parts, as follows:—Namely, at each complete revolution of the drive shaft H, the turret E is rotated one-half of a revolution, at the end of which there is a period of complete rest; another half-revolution and another period of rest completing the full cycle 120 125 130

as aforesaid, and requiring, therefor, two full revolutions of the actuator M. The periods of rest, in the rotation of the turret E, occur when the type-wheels 10, 10, are longitudinally in line with the machine, and the time occupied by said periods of rest is utilized for operating therein the impressing mechanism, depressing the sleeves 9, on the shaft 8, on which the operative type is mounted, 10 and for synchronizing the opposite type-wheel 10.

The synchronizing mechanism consists of cams 12, 12, Figs. 1, 6 and 7, rigidly secured on the shafts 8, 8; the reciprocating cam-operator 13, carrying a knife-edged stud 13^a, and mounted in slideways 13^b, firmly secured to the frame of the machine; the duplex-armed, angular lever 14, with the arms 14^b, and 14^c, 14^c, fulcrumed on a horizontal fixed 20 pivot P; a link 14^a, pivotally connected at one end to the short arm of the lever 14; the other end thereof being slotted to embrace the drive shaft H, and a cam-roller h³, operated by a cam H³. Each cam 12, as shown 25 herein, consists of two oppositely-spiral radial vanes meeting and joined at their lower extremities and forming a single radial knife-edge, their upper extremities being separated by a space sufficient to receive the 30 knife-edged portion of the stud 13^a, on the cam operator 13.

The cam H³, on the drive shaft H, is so designed as to operate the synchronizing mechanism when the turret E is at one of the two 35 zero points at which the latter is at rest.

In operation, the turret E, being at rest, as aforesaid, and the shafts 8, 8, being in line with the knife-edge on the stud 13^a, the cam H³, on the drive shaft H, by means of the 40 cam-roller h³, and the link 14^a, moves forward, the arm 14^b, of the lever 14; thus raising the arms 14^c, 14^c, of the latter, and by means thereof, raising the cam-operator 13, with the stud 13^a, the knife-edged portion of the 45 latter engaging, in its ascent, the cam 12, which is on the shaft 8, which the immediately-precedent partial rotation of the turret E, has brought into the proper relative position for such engagement; the further 50 continuous movement of the cam-operator 13, partly rotates the cam 12, shaft 8, and type-wheel 10; the completion of the movement of the cam-operator 13, causing a complete interposition of the knife-edged portion 55 of the stud 13^a, in the opening at the upper end of the cam 12, fixing the type-wheel 10, and the sleeve 9, carrying a tappet 9^b, and a gear-wheel 9^c all in position for their proper operation by any one of the keys 1, and the train of selective mechanism to and 60 including its correlative latch 6. Continued rotation of the cam H³, and its operated train, depresses the cam-operator 13, carrying the stud 13^a, to a point below the rotary plane of the cams 12, 12.

The impressing, feeding and inking mechanisms may be of any desired operative form, such, for instance, as shown, where the former consists of an impressing cylinder R', and a feed roller R², Fig. 4, mounted in a carriage R; impressions being made by bringing the paper or other material mounted on the cylinder R', against the nearest type on a type-wheel 10, by means of a lever r, Figs. 1, 4 and 5, oscillated on the fixed pivot P, by 70 means of a link r', cam-roller h', and the cam H' on the drive shaft H. The inking devices, if used, may, in form, be as shown at S, S, Fig. 4; where spring-operated levers S', S', hold the ink-rollers S'', S'', in position to 80 engage the types A, B, C, etc., when the type-wheels 10, 10, are rotated.

Having described my invention, I claim—

1. The combination of a plurality of trains of selective mechanism, an intermittently and variably operative driven member carrying a cam, a cam operator engageable with the cam at any point in the operation of the driven member and operating said cam and its connections, for effecting a normal adjustment of the driven member relative to the several trains of selective mechanism. 90

2. The combination of a plurality of trains of selective mechanism, an intermittently and variably rotative driven member carrying a cam, a cam operator engageable with the cam at any point in the rotation of the driven member and operating said cam and its connections, for effecting a normal adjustment of the driven member relative to 100 the several trains of selective mechanism.

3. The combination of a plurality of trains of selective mechanism, a plurality of intermittently and variably operative driven members each carrying a cam, a cam operator engageable with any one of the cams at any point in the operation of its connected driven member and operating said cam and its connections, for effecting a normal adjustment of the driven member relative to the 110 several trains of selective mechanism.

4. The combination of a plurality of trains of selective mechanism, a plurality of differential impression devices mounted upon an intermittently and variably operated driven member carrying a cam, a cam operator engageable with the cam at any point in the operation of the driven member and operating said cam and its connections, for effecting a normal adjustment of the impression devices relative to the several trains of selective mechanism. 115

5. The combination of a plurality of trains of selective mechanism, a plurality of differential impression devices mounted upon an intermittently and variably rotated driven member carrying a cam, a cam operator engageable with the cam at any point in the rotation of the driven member and operating said cam and its connections, for effecting a 125 130

- normal adjustment of the impression devices relative to the several trains of selective mechanism.
6. The combination of a plurality of trains of selective mechanism, a plurality of series of differential impression devices mounted upon a plurality of intermittently and variably operated driven members each carrying a cam, a cam operator engageable with any one of the cams at any point in the operation of its connected driven member and operating said cam and its connections, for effecting a normal adjustment of the impression devices relative to the several trains of selective mechanism.
7. The combination of a plurality of trains of selective mechanism, an intermittently and variably operative driven member carrying a cam, the latter being formed with oppositely spiral radial vanes acutely joined at the extreme initial point of operation of said cam and located in a common operative plane, a cam operator engageable with the cam at any point in the operation of the driven member and operating said cam and its connections, for effecting a normal adjustment of the driven member relative to the several trains of selective mechanism.
8. The combination of a plurality of trains of selective mechanism, a cam formed with oppositely spiral radial vanes acutely joined at the extreme initial point of operation of said cam and located in a common rotative plane on an intermittently and variably rotative driven member, and a reciprocatable cam operator engageable with the cam at any point in the operation of the driven member and operating said cam and its connections, for effecting a normal adjustment of the driven member relative to the several trains of selective mechanism.
9. The combination of a plurality of trains of selective mechanism, a plurality of differential impression devices mounted upon an intermittently and variably rotated driven member carrying a cam formed with oppositely spiral radial vanes acutely joined at the extreme initial point of operation of said cam and located in a common rotative plane, a cam operator engageable with said cam at any point in the operation of the driven member and operating said cam and its connections, for effecting a normal adjustment of the driven member relative to the several trains of selective mechanism.
10. The combination of a plurality of trains of selective mechanism, a plurality of differential impression devices mounted upon an intermittently and variably rotated driven member carrying a cam formed with oppositely spiral radial vanes acutely joined at the extreme initial point of operation of said cam and located in a common rotative plane, a reciprocatable cam operator engageable with said cam at any point in the operation of the driven member and operating said cam and its connections, for effecting a normal adjustment of the driven member relative to the several trains of selective mechanism.
11. The combination of a plurality of trains of selective mechanism, an intermittently and variably operative driven member carrying a cam the latter being formed with oppositely spiral radial vanes acutely joined at the extreme initial point of operation of said cam and located in a common operative plane, a reciprocatable cam operator engageable with the cam at any point in the operation of the driven member and operating said cam and its connections, for effecting a normal adjustment of the driven member relative to the several trains of selective mechanism.
12. The combination of a plurality of trains of selective mechanism, an intermittently and variably rotative driven member carrying a cam the latter being formed with oppositely spiral radial vanes acutely joined at the extreme initial point of operation of said cam and located in a common rotative plane, a cam operator engageable with the cam at any point in the rotation of the driven member and operating said cam and its connections, for effecting a normal adjustment of the driven member relative to the several trains of selective mechanism.
13. The combination of a plurality of trains of selective mechanism, an intermittently and variably rotative driven member carrying a cam the latter being formed with oppositely spiral radial vanes acutely joined at the extreme initial point of operation of said cam and located in a common rotative plane, a reciprocatable cam operator engageable with the cam at any point in the rotation of the driven member and operating said cam and its connections, for effecting a normal adjustment of the driven member relative to the several trains of selective mechanism.
14. The combination of a plurality of trains of selective mechanism, a plurality of intermittently and variably operative driven members each carrying a cam the latter being formed with oppositely spiral radial vanes acutely joined at the extreme initial point of operation of said cam and located in a common operative plane, a cam operator engageable with any one of the cams at any point in the operation of its connected driven member and operating said cam and its connections, for effecting a normal adjustment of the driven member relative to the several trains of selective mechanism.
15. The combination of a plurality of trains of selective mechanism, a plurality of intermittently and variably operative driven members each carrying a cam the latter being formed with oppositely spiral radial vanes acutely joined at the extreme initial point of operation of said cam and located in a common operative plane, a reciprocatable cam operator engageable with the cam at any point in the operation of the driven member and operating said cam and its connections, for effecting a normal adjustment of the driven member relative to the several trains of selective mechanism.

vanes acutely joined at the extreme initial point of operation of said cam and located in a common rotative plane, a reciprocatable cam operator engageable with any one of the 5 cams at any point in the operation of its connected driven member and operating said cam and its connections, for effecting a normal adjustment of the driven member relative to the several trains of selective mechanism.

16. The combination of a plurality of trains of selective mechanism, a plurality of differential impression devices mounted upon an intermittently and variably operated driven member carrying a cam the latter being formed with oppositely spiral radial vanes acutely joined at the extreme initial point of operation of said cam and located in a common operative plane, a cam 20 operator engageable with the cam at any point in the operation of the driven member and operating said cam and its connections, for effecting a normal adjustment of the impression devices relative to the several 25 trains of selective mechanism.

17. The combination of a plurality of trains of selective mechanism, a plurality of differential impression devices mounted upon an intermittently and variably operated 30 driven member carrying a cam the latter being formed with oppositely spiral radial vanes acutely joined at the extreme initial point of operation of said cam and located in a common operative plane, a reciprocatable 35 cam operator engageable with the cam at any point in the operation of the driven member and operating said cam and its connections, for effecting a normal adjustment of the impression devices relative to the several trains 40 of selective mechanism.

18. The combination of a plurality of trains of selective mechanism, a plurality of series of differential impression devices mounted upon intermittently and variably 45 rotated driven members each carrying a cam the latter being formed with oppositely spiral radial vanes acutely joined at the extreme initial point of operation of said cam and located in a common rotative plane, a cam 50 operator engageable with each cam at any point in the rotation of its connected driven member and operating said cam and its connections, for effecting a normal adjustment of the impression devices relative to the 55 several trains of selective mechanism.

19. The combination of a plurality of trains of selective mechanism, a plurality of series of differential impression devices mounted upon intermittently and variably 60 rotated driven members each carrying a cam the latter being formed with oppositely spiral radial vanes acutely joined at the extreme initial point of operation of said cam and located in a common rotative plane, a

reciprocatable cam operator engageable with 65 each cam at any point in the rotation of its connected driven member and operating said cam and its connections, for effecting a normal adjustment of the impression devices relative to the several trains of selective 70 mechanism.

20. The combination of a plurality of trains of selective mechanism, a plurality of series of differential impression devices mounted upon a plurality of intermittently 75 and variably operated driven members carrying a cam the latter being formed with oppositely spiral radial vanes acutely joined at the extreme initial point of operation of said cam and located in a common operative 80 plane, a cam operator engageable with any one of the cams at any point in the operation of its connected driven member and operating said cam and its connections, for effecting a normal adjustment of the impression devices relative to the several trains of selective 85 mechanism.

21. The combination of a plurality of trains of selective mechanism, a plurality of series of differential impression devices 90 mounted upon a plurality of intermittently and variably operated driven members carrying a cam, the latter being formed with oppositely spiral radial vanes acutely joined at the extreme initial point of operation of said 95 cam and located in a common operative plane, a reciprocatable cam operator engageable with any one of the cams at any point in the operation of its connected driven member and operating said cam and its connections, 100 for effecting a normal adjustment of the impression devices relatively to the several trains of selective mechanism.

22. The combination of an orbitally mounted rotatable series of impression devices, a driven member mounted on the axis of said series and intermittently engaging a driving member, a disengaging member, and a reciprocating member engaging said disengaging member for disengaging the driven 110 member from the driving member.

23. The combination of a rotatably mounted series of impression devices, a driven member mounted on the axis of said series and intermittently engaging a driving member, a 115 disengaging member attached to the driven member and a reciprocating member engaging said disengaging member for disengaging the driven member from the driving member.

24. The combination of an intermittently rotatable series of impression devices, a driven member mounted on the axis of said series and intermittently engaging a driving member, a disengaging member attached to 125 the driven member, a reciprocating member engaging said disengaging member for disengaging the driven member from the driving

member, synchronously with the intermissions in the rotation of the series of impression devices.

25. The combination of a plurality of independently rotatable series of impression devices, a plurality of driven members, severally mounted on the respective axes of said series and all and severally intermittently engaging one driving member, a plurality of disengaging members severally attached to the respective driven members, and a reciprocating member alternately engaging said disengaging members for alternately disengaging the several driven members from the driving member.

26. The combination of an orbitally mounted series of impression devices intermittently rotated, a driven member mounted on the axis of said series and intermittently engaging a driving member, a disengaging member attached to the driven member, a reciprocating member engaging said disengaging member for disengaging the driven member from the driving member synchronously with the intermissions in the rotation of the series of impression devices.

27. The combination of a plurality of orbitally mounted series of impression devices severally intermittently rotated, a plurality of driven members severally mounted on the respective axes of said series and severally intermittently engaging a driving member, a plurality of disengaging members severally attached to the respective driven members, a reciprocating member alternately engaging said disengaging members for alternately disengaging the several driven members from the driving member, synchronously with the intermissions in the orbital rotations of the several series of impression devices.

28. The combination of a plurality of selective mechanisms, an intermittently and variably operated driven member carrying a detent, an operator engageable with said detent at any point in the operation of its connected driven member for operating said detent and its connections and effecting a normal adjustment of the driven member relative to the several selective mechanisms.

29. The combination with a plurality of carriers and a plurality of impression devices mounted on each carrier and mechanism for actuating the carriers to thereby shift the selected impression device toward and away from the working point, and for arresting the motion of the selected carrier when the selected impression device is at the working point, and a synchronizing device comprising a synchronizing slide for returning the selected carrier to a fixed predetermined position.

30. The combination with a plurality of carriers, of a plurality of impression devices mounted on each carrier and mechanism for actuating the carriers to thereby shift the

selected impression device toward and away from the working point, and for arresting the motion of the selected carrier when the selected impression device is at the working point, a synchronizing device comprising a synchronizing slide for returning the selected carrier to a fixed predetermined position, and means for actuating said slide for effecting the shifting of the carrier to its predetermined position during the temporary suspension of the motion of the carriers.

31. The combination with a plurality of carriers adapted for independent rotary movements and for orbital movement past the working point, of a plurality of impression devices mounted on each carrier, mechanism for causing said carriers to move along their orbital path and for arresting the carrier supporting the selected impression device when such device is at the working point, selective mechanism for selecting one impression device to the exclusion of the others, and means comprising a shiftable slide for returning the selected carrier to a predetermined rotary position.

32. The combination with a plurality of carriers adapted for independent rotary movements and for orbital movement past the working point, of a plurality of impression devices mounted on each carrier, mechanism for causing said carriers to move along their orbital path and for arresting the carrier supporting the selected impression device, when such device is at the working point, selective mechanism for selecting one impression device to the exclusion of the others, and means comprising inclined working faces moving in unison with such carriers, and a synchronizing slide to coöperate with said faces for returning the selected carrier to its predetermined rotary position.

33. The combination with a turret, of a plurality of rotatable impression device carriers mounted thereon, mechanism for imparting an intermittent movement to said turret to bring each impression device carrier in succession to the working point and then cause the motion of the turret to be temporarily suspended, a starting arm rotatable in unison with each impression device carrier, selective mechanism for engaging a starting arm and initiating the rotary movement of the selected impression device carrier prior to the arrival thereof at the working point, and a synchronizing device comprising inclined working faces moving in unison with each impression device carrier, and a synchronizing slide coöoperative with an inclined face when the selected impression device carrier shall have been withdrawn from the working point.

34. The combination with an intermittently rotatable turret, of a plurality of impression device carriers whose shafts are mounted on said turrets, a starting arm ex-

tending from each of said shafts, selective mechanism for engaging with the respective starting arms, driving means for continuing the rotary movement of a selected impression device carrier subsequent to the initiation of such movement by its engaged starting arm, means for throwing said driving means out of gear when the selected carrier has been withdrawn from the working point, 10 and a synchronizing slide for returning such carrier to its predetermined rotary position.

35. The combination with a rotatable turret, of a plurality of impression device carriers whose shafts are mounted on said turret, mechanism for imparting an intermittent motion to said turret and bring each carrier in succession to the working point, an axial movable gear mounted on each impression device carrier shaft, a fixed driving gear, 20 starting means comprising starting arms and selective mechanism for initiating the rotary movement of an impression device carrier prior to its arrival at the working point, cam devices for shifting the said gear on each selected carrier shaft axially upon the initiation of the rotary movement thereof, a cam operated retractor for disengaging the engaged gear when the selected impression device carrier shall have been withdrawn from 30 the working point, and a synchronizing slide for returning said carrier and its shaft and gear to a predetermined rotary position.

36. The combination of a plurality of selective mechanisms, an intermittently and 35 variably rotative driven member carrying a detent, an operator engageable with the detent at any point in the operation of its connected driven member for operating said detent and its connections and effecting a normal 40 rotative adjustment of the driven member relatively to the several selective mechanisms.

37. The combination of a plurality of selective mechanisms, a plurality of intermittently and variably driven members each carrying a detent, an operator engageable with any one of the detents at any point in the operation of its connected driven member and operating said detent and its connections for effecting a normal adjustment of the driving member relatively to the several selective mechanisms.

38. The combination of a plurality of trains of selective mechanisms, an intermittently and variably operative driven member carrying a detent, an operator engageable with said detent at any point in the operation of its connected driven member and operating said detent and its connections for effecting a normal adjustment of the driven member relatively to the several trains of selective mechanisms.

39. The combination of a plurality of trains of selective mechanisms, an intermittently and variably rotative driven member

carrying a detent, an operator engageable with the detent at any point in the rotation of its connected driven member and operating said detent and its connections for effecting a normal adjustment of the driven member relatively to the several trains of selective mechanisms.

40. The combination of a plurality of trains of selective mechanisms, a plurality of intermittently and variably operated driven members, each carrying a detent, an operator engageable with any one of the detents at any point in the operation of its connected driven member and operating said detent and its connections, for effecting a normal adjustment of the driven member relatively to the several trains of selective mechanisms.

41. The combination of selective mechanism, differential impression devices mounted upon an intermittently and variably operated driven member carrying a detent, an operator engageable with the detent at any point in the operation of its connected driven member and operating said detent and its connections, for effecting a normal adjustment of the impression devices relatively to the several trains of selective mechanisms.

42. The combination of a plurality of trains of selective mechanisms, a plurality of differential impression devices mounted upon an intermittently and variably operated driven member carrying a detent, an operator engaging with said detent at any point in the operation of its connected driven member and operating said detent and its connections for effecting a normal adjustment of the impression device relatively to the several trains of selective mechanisms.

43. The combination of selective mechanism differential impression devices mounted upon intermittently and variably operated driven members, each carrying a detent, an operator engageable with any one of the detents at any point in the operation of its connected driven member and operating said detent and its connections, for effecting a normal adjustment of the impression devices relatively to the selective mechanism.

44. The combination of a train of selective mechanisms, a series of differential impression devices mounted upon an intermittently and variably driven member carrying a detent, an operator engaging with said detent at any point in the actuation of its connected driven member and operating said detent and its connections for effecting a normal adjustment of the impression devices relatively to the selective mechanisms.

45. The combination of a series of impression devices intermittently actuated, a driven member intermittently engaging a driving member, a disengaging member attached to its connected driven member, a reciprocating member engaging said disengaging member for disengaging the driven member from

the driving member synchronously with the intermissions in the rotation of the series of impression devices.

46. The combination with a plurality of carriers, of a plurality of intermittently rotating impression devices mounted thereon, and mechanism to actuate the carriers to shift the selected impression device in various relations to the working point and for 10 stopping the motion of the selected carrier when the selected impression device is at the working point.

47. The combination with a plurality of carriers, of a plurality of intermittently and 15 variably rotating impression devices mounted on each carrier, and mechanisms for actuating the carriers to shift the selected impression device in various relations with respect to the working point, and for arresting 20 the motion of the selected carrier when the selected impression device is at the working point.

48. The combination with a mechanically 25 actuatable impression device carrier, of mechanism for rotating the same with respect to the working point of a blank and for temporarily arresting the motion thereof when the same is at such point, and means for returning the carrier to a fixed position 30 upon its recedence from the working point.

49. The combination with a mechanically 35 rotated impression device carrier, of means for directing the same toward and moving it from the working point of a blank and for temporarily arresting the motion of the device when the same is at such working point, and a synchronizing device for fixing the position of the carrier upon its being withdrawn from said working point.

50. The combination of an intermittently and variably operating driven member, a tappet mounted thereon and operating therewith, a series of keys severally engageable with said tappet, a cam, formed 45 with oppositely spiral radial working faces acutely joined at a contacting point, said cam being mounted upon said driven member, a cam operator engageable with said cam at any point in the operation of the driven member and adapted to operate said cam and its connections for effecting a normal adjustment of the driven member relative to the several detents in the series.

51. The combination of an intermittently 55 and variably operating driven member, a tappet mounted thereon and operating therewith, a series of selective devices severally engageable with said tappet, a cam, formed with oppositely spiral radial working faces 60 acutely joined at a contacting point, said cam being mounted upon said driven member, and a cam operator engageable with said cam at any point in the operation of the driven member and adapted to operate said cam and its connection for effecting a

normal adjustment of the driven member relative to the several selective devices.

52. The combination of an intermittently and variably rotating driven member, a tappet mounted upon and rotating therewith, 70 a series of detents which engage with said tappet and stop it at different angular positions, and means for returning said driven member after each engagement of the tappet and a projected key to a fixed normal position. 75

53. The combination of an intermittently and variably rotating driven member, a tappet mounted upon and rotating therewith, 80 a series of selective devices which engage with said tappet and stop it at different angular positions, and means for returning said driven member after each engagement of the tappet and a projected key to a fixed normal position. 85

54. The combination of a plurality of differential impression devices mounted upon an intermittently operating driven member carrying a tappet, the latter being engageable by any of the several keys of a series, and means 90 for returning said driven member after each engagement of the tappet and a projected key to a fixed normal position.

55. The combination of a plurality of differential impression devices mounted 95 upon an intermittently operating driven member carrying a tappet, the latter being engageable by any of the several selective devices of a series, and means for returning said driven member after each engagement 100 of the tappet and a projected key to a fixed normal position.

56. An intermittently and variably rotated member, a cam mounted thereon and formed with oppositely spiral vanes mounted in a common plane of rotation and acutely joined at a contacting point, and a cam operator engageable with said cam at any point in the operation of the rotating member and adapted to operate said cam and its connections for effecting a normal adjustment of the rotating member relative to a series of selective devices severally engageable with a tappet mounted on and rotating with the rotating member, and a series of latches 115 severally engageable with the series of selective devices.

57. An intermittently and variably rotated member, a cam mounted thereon and formed with oppositely spiral vanes mounted in a 120 common plane of rotation and acutely joined at a contacting point, and a cam operator engageable with said cam at any point in the operation of the rotating member and adapted to operate said cam and its 125 connections for effecting a normal adjustment of the rotating member relative to a series of selective devices severally engageable with a tappet mounted on and rotating with the rotating member, and a series of 130

latches severally engageable with any one of the respective selective devices.

58. An intermittently and variably rotated member, a cam mounted thereon and formed with oppositely spiral vanes mounted in a common plane of rotation and acutely joined at a contacting point, a cam operator engageable with said cam at any point in the operation of the rotating member and adapted to 10 operate said cam and its connections for effecting a normal adjustment of the rotating member relative to a series of keys severally engageable with a tappet mounted on and rotating with the rotating member, and a series of latches severally engageable with the respective keys.

59. An intermittently and variably rotated member, a cam mounted thereon and formed with oppositely spiral vanes mounted in a common plane of rotation and acutely joined at a contacting point, a cam operator engageable with said cam at any point in the operation of the rotating member and adapted to 15 operate said cam and its connections for effecting a normal adjustment of the rotating member relative to a series of keys severally engageable with a tappet mounted on and rotating with the rotating member, and a series of latches severally engageable with the respective keys in said series.

60. A plurality of differential impression devices mounted on an intermittently and variably rotating member carrying a tappet, a series of selective devices severally engageable with said tappet, a series of latches severally engageable with the respective selective devices, a latch, a cam mounted upon the rotating member and formed with oppositely spiral vanes mounted in a common plane, and a cam operator engageable with said cam at any point in the operation of the rotating member and adapted to operate said cam and its connections for effecting a normal adjustment of the rotating member relative to the several selective devices.

61. A plurality of differential impression

devices mounted on an intermittently and variably rotated member carrying a tappet, a series of selective devices severally engageable with said tappet, a series of latches severally engageable with the respective selective devices a latch, a cam mounted upon the rotating member and formed with oppositely spiral vanes mounted in a common plane, and a cam operator engageable with said cam at any point in the operation of the rotating member and adapted to operate said cam and its connections for effecting a normal adjustment of the driven member relative to the several selective devices.

62. A plurality of differential impression devices mounted on an intermittently and variably rotated member carrying a tappet, a series of keys severally engageable with said tappet, a series of latches severally engageable with the respective keys, a latch, a cam mounted upon the rotating member and formed with oppositely spiral vanes mounted in a common plane, and a cam operator engageable with said cam at any point in the operation of the rotated member and adapted to operate said cam and its connection for effecting a normal adjustment of the driven member relative to the several keys.

63. A plurality of impression devices mounted on an intermittently and variably rotated member carrying a tappet, a series of keys severally engageable with said tappet, a series of latches severally engageable with the respective keys, a cam mounted upon the rotated member and formed with oppositely spiral vanes mounted in a common plane, and a cam operator engageable with said cam at any point in the operation of the driven member and adapted to operate said cam and its connection for effecting a normal adjustment of the rotating member relative to the several keys.
